UNITED STATES PATENT OFFICE.

SHERMAN BLAIR, OF MCKEESPORT, PENNSYLVANIA.

RAIL-JOINT.

SPECIFICATION forming part of Letters Patent No. 691,525, dated January 21, 1902.

Application filed May 23, 1901. Serial No. 61,540. (No model.)

To all whom it may concern:

Be it known that I, SHERMAN BLAIR, a citizen of the United States of America, residing at McKeesport, in the county of Allegheny and State of Pennsylvania, have invented 5 certain new and useful Improvements in Rail-Joints, of which the following is a specification, reference being had therein to the accompanying drawings.

10 This invention relates to certain new and useful improvements in rail-joints, and relates more particularly to that class wherein the use of nuts and bolts is entirely dispensed with.

15 The present invention has for its object the provision of novel means whereby interlocking fish-plates are employed that will form a substantially rigid rail connection; furthermore, to provide novel means whereby the 20 expansion and contraction are provided for in this class of joints.

25 This invention has for its still further object to construct a rail-joint of the above class that will be extremely simple in construction, strong, durable, and comparatively inexpensive to manufacture.

30 With the above and other objects in view the invention consists in the novel combination and arrangement of parts to be herein- 35 after more fully described, and specifically pointed out in the claims.

35 In describing the invention in detail reference is had to the accompanying drawings, forming a part of this specification, and 40 wherein like numerals of reference indicate corresponding parts throughout the several views, in which—

45 Figure 1 is a side elevation of a portion of two rails having attached thereto my improvements. Fig. 2 is a top plan view thereof. Fig. 3 is a longitudinal sectional view taken through the web of the rail immediately below the tread. Fig. 4 is an enlarged perspective view of one of the interlocking fish-plates. Fig. 5 is a similar view of the 50 other interlocking fish-plate. Fig. 6 is a cross-sectional view taken on the line 6 6 of Fig. 2.

55 In the drawings the reference-numeral 1 indicates the rails, which are of the ordinary construction. In the end of the web are formed openings 2. On each side of said

openings are formed through the web enlarged openings 3 3.

5 The reference-numeral 4 represents one of 55 the interlocking fish-plates, carrying on its one face an inwardly-extending projection 5, which projection is seated in the recesses 2 2 of the web of the rail. The said interlocking fish-plates carry on each end projections 6 6, extending into the openings 3 3.

6 The reference-numeral 7 indicates the opposite interlocking fish-plate carrying hooked ends 8, which hooked ends also extend through the openings 3 3 and engage the end of the 65 outer face of the fish-plate 4, forming a locking connection therewith. These hooked ends 8 are formed of spring-steel or the like in order that they may be given a wedging action as they are driven in place and will 70 spring in proper position to engage the outer face of the fish-plate 4, thereby forming a locking connection therewith.

7 Denotes a base-plate, which may be formed integral with one or both of the locking fish- 75 plates and adapted to extend beyond the base of the rail. This base-plate is secured to the ties in any suitable manner.

8 The many advantages obtained by the use of my improved rail-joint will be readily apparent from the foregoing description, taken 80 in connection with the accompanying drawings.

85 It will be noted that various changes may be made in the details of construction without departing from the general spirit of my invention.

90 Having fully described my invention, what I claim as new, and desire to secure by Letters Patent, is—

95 1. In a rail-joint, the combination of two interlocking fish-plates, one of said fish-plates carrying projections on each end and extending through the web of the rail, the other of said fish-plates carrying a pair of hooked portions one on each end extending through the web of the rail and engaging the outer face of said first-named fish-plate, substantially as described.

100 2. In a rail-joint, the combination of two interlocking fish-plates, upper and lower engaging faces on said fish-plates, projections made integral with one of said fish-plates extending through the web of the rails, hooked

portions made integral with other of said fish-plates extending through the web of the rail and engaging the outer face of the said first-named fish-plate, substantially as described.

5. 3. In a rail-joint, the combination of two interlocking fish-plates, one of said fish-plates carrying projections extending through the web of the rail, and the other interlocking fish-plate carrying hooked portions extending through the web of the rail and engaging the outer face of the first-named fish-plate, all parts being arranged and operating substantially as described.

4. In a rail-joint, a fish-plate, upper and lower beveled engaging faces thereon, projections made integral with said fish-plate extending through the web of the rail, a second fish-plate, a base secured thereto, upper and lower beveled engaging faces thereon, 20 hooked portions made integral with said fish-

plate extending through the web of the rail and engaging the outer face of the first-named fish-plate, substantially as described.

5. In a rail-joint, the combination of a base-plate, a fish-plate made integral therewith, 25 upper and lower engaging faces on said fish-plate, hooked portions carried by said fish-plate on each end thereof, a second fish-plate, upper and lower engaging faces thereon, projections carried by said fish-plate, the said 30 hooked portions adapted to engage the outer face of said second-named fish-plate, substantially as described.

In testimony whereof I affix my signature in the presence of two witnesses.

SHERMAN BLAIR.
